UNITED STATES PATENT OFFICE.

EDWARD H. REMPE AND FREDERICK M. ROSS, OF OAKLEY, OHIO.

AUTOMATIC SASH-LOCK.

1,023,442.

Specification of Letters Patent.

Patented Apr. 16, 1912.

Application filed January 16, 1911. Serial No. 602,756.

To all whom it may concern:

Be it known that we, EDWARD H. REMPE and FREDERICK M. ROSS, citizens of the United States of America, and residents of 5 Oakley, county of Hamilton, and State of Ohio, have invented certain new and useful Improvements in Automatic Sash-Locks, of which the following is a specification.

This invention relates to window locks 10 and has for an object to provide means for locking the upper and lower sash of a window together, which cannot be tampered with or unlocked from the outside.

A further object is to produce a window 15 lock which will automatically move from a set to a locked position, when the window is closed.

These and other objects we attain by 20 means of a device embodying the features herein described, and illustrated in the drawings accompanying this application and forming a part of it.

In the drawings, Figure 1 is a sectional view of a lock embodying our invention, 25 shown in the set position, and in connection with a fragmental sectional view of the upper and lower sash of a window. Fig. 2 is a sectional view corresponding to Fig. 1, and showing the window sash closed and 30 the lock locked. Fig. 3 is a sectional view corresponding to Figs. 1 and 2, and shows the lock in the release position, so that its bolt or latch can be automatically withdrawn from the keeper, as the window is 35 opened.

The lock illustrated as an embodiment of our invention, consists of a pivotally mounted bolt or latch 4, a manually actuated lever or handle 5, for engaging the bolt, and for 40 positively locking it in the locked position, and a keeper 6, which engages the end of the latch, when it is moved to the locked position. The handle 5 and the latch 4 are mounted within a casing 7, which is secured 45 by any suitable means, such, for example, as screws, to the top of the lower sash 8 of the window. The keeper 6 is secured to the bottom of the upper sash 9 of the window in such a position, that it is located immediately adjacent to the casing 7, when the window is closed. The latch 4 is pivotally mounted on a pin 11, which extends transversely across the casing 7, and is so located 50 that the lower end of the latch projects through a slot formed in the rear face of the casing 7, and is adapted to swing from a set

position to an operative position, to engage a keeper pin 12, when one sash is moved relatively to the other sash to a closed position. Latch 4, in the set position, contacts 60 with the lower face 13 of the casing. A slot 14 is formed partially in the top and partially in the forward face of the keeper 6, and is of such width in the top face of the keeper, that the latch can move downwardly 65 into it, when in the set position. The lower edge 15 of the slot 14 is preferably, but not necessarily, slightly beveled inwardly with reference to the keeper, and the lower end of the inner edge of the latch 4 is curved, so 70 that it coöperates with the edge 15 to swing the latch 4 outwardly to the locked position, when the window sashes are moved to the closed position. The outer edge of the latch 4 is curved near the outer end to form a 75 hook which is adapted to engage the keeper pin 12, when the latch is moved to the locked position. The inner end of the latch is provided with a knuckle 17', which terminates in an extension 17. The extension 17 is 80 adapted to engage a notch 18 provided on the inner end of the handle 5, when the latch is moved to the locked position. The handle 5 is pivotally mounted on a pin 19, mounted in the casing 7, and projects 85 through a slot formed in the forward face of the casing. The inner end of the handle is curved to form a cam-face 20, which is so located that it engages the knuckle 17', when the latch is in the set position, and which 90 terminates in the notch 18. The point of the cam face 20 which is at the greatest distance from the pivot 19, is at notch 18. The movement of handle 5 in a clockwise direction therefore does not move latch 4, when 95 it is in its set position. As the latch 4 is moved from the set to the locked position, by the edge 15 of the keeper 6, the inner edge of the latch slides along the cam-face 20, until the notch 18 trips into engagement 100 with the extension 17 and positively locks the latch in place.

When the latch is in place, it cannot be moved, unless released by the handle 5, since it is firmly held against turning about the pin 105 11 by three rigid points of support; to-wit, the pin 12, the edge 15 and the point of engagement between the recess 18 of the handle and the extension 17 of the latch. The engagement between the extension 17 110 and the notch 18, prevents a clockwise motion of the latch around the pin 11, and

the pin 12 prevents a contra-clockwise motion. Under these conditions, the upper and the lower sash are firmly locked together against relatively vertical motion, and they are also locked against relatively lateral motion, by the engagement of the curved end of the latch with the keeper pin 12, and, consequently, the lock cannot be tampered with, or unlocked, by inserting a 10 knife blade, or other instrument, between the sash, from the outside of the window.

In releasing the latch 4, or unlocking the window, the handle 5 is raised to a vertical position, as shown in Fig. 3. Its center of 15 gravity is so located, that it will remain in this vertical position, until tripped by the latch 4. When the handle is in the release or vertical position, the extension 17 is free from the notch 18, and the window can be 20 opened. The opening motion of either sash, will turn the latch 4 about its mounting pin 11 and the pin 12 in leaving the end of the latch, will move it to the set position against the face 13. The cam-face 20 of the 25 handle 5 is provided with an extension, so formed that the first movement of the latch from the locked toward the set position, causes the extension 17 to engage the extension of the cam 20 and to trip the handle 30 and causes it to swing around its mounting pin from the vertical or release position to the set position. With this arrangement, the window can not be closed, without being automatically locked, since, as has been 35 described, the opening motion of either sash, moves the latch 4 and the handle 5 to the set position, and since the set position of the latch cannot be disturbed by a manipulation of the handle 5.

What we claim is:—

1. A window lock comprising a frame, a 40 latch pivotally mounted on said frame and adapted to swing to occupy a set and a locked position, a handle pivotally mounted on said frame and provided with means for locking said latch in a locked position, and means for engaging said latch to cause said handle to move from a release to a set position, a keeper provided with an edge for engaging said latch and moving it from a set 45 to a locked position, and a pin mounted on said keeper for engaging said latch and co-operating with said handle for locking said latch in a locked position.

2. In a sash lock, the combination of a 50 casing for the lower sash, a keeper for the upper sash, two journaled pins mounted in the casing, a latch mounted upon the forward journaled pin in the casing and having a rearwardly extending projection, a 55 handle mounted upon the other journaled pin in the casing having a cam face adjacent to the latch, the lower edge of the cam face terminating in a notch which engages the rearward extension of the latch in its set position, a detaining pin within the keeper adapted to contact with the upper face of the latch in its set position and to pass the latch in its released position, and the keeper being adapted to engage the latch when the 60 upper sash is being closed to move the latch to its set position.

EDWARD H. REMPE.
FREDERICK M. ROSS.
